CLAIM

The ornamental design for a solar panel, as shown and described.

DESCRIPTION

FIG. 1 is a top plan view of a solar panel showing our new design;

FIG. 2 is a close-up view of a portion of the solar panel of FIG. 1;

FIG. 3 is a top plan view of a solar panel according to another embodiment of our design;

FIG. 4 is close-up view of a portion of the solar panel of FIG. 3;

FIG. 5 is a top plan view of a solar panel according to another embodiment of our design;

FIG. 6 is close-up view of a portion of the solar panel of FIG. 5;

FIG. 7 is a top plan view of a solar panel according to another embodiment of our design;

FIG. 8 is close-up view of a portion of the solar panel of FIG. 7;

FIG. 9 is a top plan view of a solar panel according to another embodiment of our design;

FIG. 10 is close-up view of a portion of the solar panel of FIG. 9;

FIG. 11 is a top plan view of a solar panel according to another embodiment of our design;

(Continued)

FIG. 12 is close-up view of a portion of the solar panel of FIG. 11;

FIG. 13 is a top plan view of a solar panel according to another embodiment of our design; and,

FIG. 14 is a close-up view of a portion of the solar panel of FIG. 13.

1 Claim, 14 Drawing Sheets**Related U.S. Application Data**

and a continuation-in-part of application No. 29/694, 773, filed on Jun. 13, 2019, now abandoned.
